Hawkins & Hawson

UNITED STATES PATENT OFFICE

CHARLES H. MERROW, OF BROCKTON, MASSACHUSETTS

SHOE WELT

Application filed July 1, 1929. Serial No. 375,119.

This invention relates to shoe welts and more particularly to welts for light dress shoes.

An important object of the invention is the production of a shoe welt which while providing sufficient substance for withstanding the strain of the attaching stitches provides an extension edge or "iron" portion which is thin, and which accordingly does not add materially to the thickness of the sole.

A further and more specific object of the invention is the production of a single piece dual substance welt wherein the "iron" or visible extension portion of the welt is in the form of a relatively thin edge of the completed welt and is of uniform thickness throughout its width so that variation in the extent to which the welt is trimmed on edge extensions will not result in a variation of the resultant "iron" of the sole of a completed shoe.

These and other objects I attain by the construction shown in the accompanying drawings wherein I have illustrated the welt constructed in accordance with my invention and wherein:

Fig. 1 is a perspective sectional view through a portion of a shoe showing the welt in position, and

Fig. 2 is a perspective view of the welt.

Referring now more particularly to the drawings, the welt comprises a strip of material having an outer visible or "iron" extension 10 of a uniform predetermined thickness and a relatively thicker inner upper-attaching or invisible extension indicated at 11 which is preferably likewise of a uniform thickness with the exception of a slight beveling of a corner of the free edge thereof as indicated at 12 to facilitate conformation of the welt to the sole in the completed shoe.

The increase in thickness is preferably at the grooved side of the completed welt strip so that the welt may be produced from leather having a finished face 13 and will not require any subsequent finishing. The under face of the thickened invisible extension is provided with a stitch-receiving groove 14 in which the stitches 15 employed in connecting

the welt to the upper U and inner sole I may be disposed. This groove is formed immediately adjacent the inner edge of the invisible extension 11 which forms a shoulder 16 confronting the under face of the visible extension 10. A welt of this character may be very cheaply produced and will enable the production of shoes with much lighter edges than is possible with the welts now employed.

I am aware that it has heretofore been proposed to employ a welt that is wedge-shaped (termed wedge welt) wherein the substance variation is obtained by removing a wedge-shaped piece of the material, starting at nothing at the groove and cutting through to the required thickness at the outside edge, but such welts have proved impractical and the principle condemned for the reason of the varying thickness obtained on the edge extension of the shoe.

My construction overcomes this objection and allows a varying width on extension while retaining the uniformity of finished edge, or "iron", that is so necessary to a finished shoe.

As the construction employed is capable of a certain range of modification, without in any manner departing from the spirit of my invention, I do not limit myself to the specific structure herein illustrated except as herein-after claimed.

I claim:

A shoe welt comprising a unitary strip of material having when applied to the shoe an outer visible extension and an inner invisible extension of different thicknesses, the outer extension being of uniform thickness throughout its width and being the thinner, each of said extensions being free from laminae, one face of the strip being plane, the opposite face of the strip at the invisible extension and adjacent the junction of the extensions having a stitch-receiving groove.

CHARLES H. MERROW.
